UNITED STATES PATENT OFFICE.

FRANK P. D'ARCY, OF KALAMAZOO, MICHIGAN.

SPRING STRUCTURE.

1,181,995.

Specification of Letters Patent.

Patented May 9, 1916.

Application filed June 10, 1914. Serial No. 844,131.

To all whom it may concern:

Be it known that I, FRANK P. D'ARCY, a citizen of the United States, residing at Kalamazoo, in the county of Kalamazoo and State of Michigan, have invented certain new and useful Improvements in Spring Structures, of which the following is a specification.

This invention relates to improvements 10 in spring structures.

The objects of this invention are: First, to provide an improved cushion spring structure in which the front edge of the cushion is always held taut and does not 15 sag or yield under the weight of the sitter. Second, to provide in a spring structure an improved clip for securing a border wire to the spring coil. Third, to provide in a 20 structure of the class described improved means for coupling the central portions of the coil springs together.

Further objects and objects relating to 25 details and economies of construction and operation will definitely appear from the detailed description to follow.

I accomplish the objects of my invention by the devices and means described in the following specification.

The invention is clearly defined and 30 pointed out in the claims.

A structure constituting a preferred embodiment of my invention is illustrated in the accompanying drawing forming a part of this specification, in which:

Figure I is a top plan view of a structure 35 embodying my invention, the padding and fabric being removed from the top of the spring structure. Fig. II is a transverse sectional view on the irregular line 2-2 of Fig. III. Fig. III is a vertical sectional view taken on a line corresponding to the line 3-3 of Fig. I, showing the top of the spring structure covered with padding. Fig. IV is a view similar to Fig. III, showing 40 the parts in the position they assume when depressed by the weight of the sitter. Fig. V is a plan view of the blank from which the clips securing the ends of the band spring 7 are made. Fig. VI is an 45 enlarged detail sectional view of said clip taken on the line 6-6 of Fig. I. Fig. VII is an enlarged detail sectional view on the line 7-7 of Fig. VIII, showing in detail the construction of one of the clips connecting 50 the border wire with one of the spring coils. Fig. VIII is an enlarged detail sec-

tional view of said clip on the line 8-8 of Fig. VII. Fig. IX is a plan view of the blank from which said clip is made.

In the drawing, similar reference characters refer to similar parts throughout the several views, and the sectional views are taken looking in the direction of the little arrows at the ends of the section lines.

Considering the numbered parts of the drawing, my improved spring structure is provided with border wires 2, 2 at top and bottom, and wires 3 and 4 running transversely of the top and bottom frames. The top of said spring structure is covered by padding 1, which padding extends over the front edge of the cushion and is connected to the upper edge of the strip of fabric 2' with which the front edge of the cushion is finished. The coil springs 5 are secured at top and bottom to the top and bottom frames, respectively, and yieldingly support the top of the spring structure. At the front corners I provide the auxiliary springs 18 which are made of stiffer material than the coil springs 5 and which are of slightly greater diameter so that they surround the coil springs 5 at the front corners. These auxiliary springs 18 are secured at the lower end to the bottom frame and extend upwardly and are secured at their upper end to the border wire 12, which will hereinafter be described in greater detail. These auxiliary springs serve to reinforce the corners of the cushion so as to prevent the corners from sagging under a load.

I provide strips 6 extending between adjacent coils, the ends of said strips being wrapped around the wires of the spring coils 5, as clearly shown in Figs. II and IV. By this means, I prevent the centers of the coil springs from being displaced relative to each other and the coil springs are held in place substantially parallel to each other when weight is brought to bear upon them. This is of especial advantage with springs of the hour glass shape because, unless some provision such as this is made for holding the centers of the spring in place relative to each other, they have a tendency to bow out in the center when a weight is brought upon them. By providing strips such as 6 it is possible to use springs of the hour glass shape of weaker material without the danger of their bowing out in the center.

11 is a wire extending across the top frame 2 parallel to the front edge of and secured to said top frame. A plurality of band springs 7 of spring steel have a hinging connection at one end on said wire 11 by means of the clips 8. These clips 8 are made from a blank of the form shown in Fig. V, provided with a tongue 9 at one end and a slot 10 at the other end adapted to receive the tongue 9. A corresponding slot to permit the passage of the tongue 9 is formed in the end of the band spring 7 and the body of the blank 8 is wrapped around the wire 11, the tongue 9 passing through the slot provided in the end of the band spring 7 and through the corresponding slot 10 in the body of the blank 8. The tongue is then bent back upon itself securely clamping the parts of the clip together.

12 I also provide a U-shaped border wire 12 which extends across the front edge of the spring structure, as clearly shown in Figs. II, III and IV, and is secured to the coils by means of clips 13 which will be herein-after described. This border wire is attached a short distance below the top of the spring structure and the lower ends of the band springs 7 are hinged to this border wire by means of clips 8 in the same way that the upper ends are connected to the wire 11. In cases where the lower ends of the band springs 7 are adjacent the coils the clip 8 embraces not only the wire 12 but also the adjacent wire of the coil, as clearly shown in Figs. II, III, and IV.

13 In Figs. VII to IX, inclusive, I have shown one of the clips by means of which the wire 12 is secured to the spring coils. This clip consists of a body portion 13 provided with a pair of tongues 14 along one edge and a tongue 15 projecting from the central portion of the other edge. The blank from which the clip is made has a longitudinal groove 14' adapted to receive the wire 12 and a groove 15' having a curvature corresponding to the radius of the coil 5 to which it is secured so that the wire of said coil will snugly fit within said groove 15'. The tongue 15 is wrapped around the wire of coil 5 and extends over on top of the wire 12, and the tongues are wrapped around the wire 12 on either side of the tongue 15. By this means I secure a very strong and effective clip for attaching the wire 12 to the spring coil.

14 Although I have shown this clip for use in securing the wire 12 in place it will be apparent that such a clip might also be used with equal efficiency for securing the coils in place in the frames 2. It will be apparent that there is no chance for a slip or side play due to the fact that the groove 15' is constructed with a curvature corresponding to the radius of the coil.

15 From the description of the parts given

above, the operation of the structure should be very readily understood. In Fig. III, I have shown the parts as they are when in their natural position with no weight upon the cushion. When there is a weight 70 brought to bear upon the cushion, as when a person is seated upon it, the springs are depressed as shown in Fig. IV, and the band springs 7 are bowed upwardly, as shown in Fig. IV, the upper ends of said band springs 75 being carried downwardly by their connection with the top frame 2 and the parts assuming the position shown in Fig. IV. By this means, the top of the front edge of the cushion is held in substantially the same position that it occupied when the cushion was in its natural state and thus the front edge of the cushion is prevented from sagging when a weight is placed upon it and the front of the cushion is held taut at all times. 80 This construction also tends to keep the front edge of the cushion in place beneath the knees of the sitter so that a very comfortable cushion is afforded.

16 The springs 7 are made of a very fine and high grade steel possessing great resiliency and flexibility. The clips 8 may be made of soft material and form a very effective and economical hinging connection for the ends of the band springs. By means of the tie strips 6, which connect the centers of the hour glass springs 5, the springs are prevented from displacement relative to each other and from bowing out at the center thereof and it is possible to make the 95 springs of weaker material than would be the case if these tie strips were omitted.

17 I am aware that the particular structure which I have here shown may be varied considerably without departing from the spirit of my invention and, therefore, I do not wish to be restricted to the same. However, I have found this particular form to be preferred and, therefore, I desire to claim the same specifically as well as broadly as indicated by my appended claims.

18 Having thus described my invention, what I claim as new and desire to secure by Letters Patent is:

1. A spring structure comprising top and bottom frames, coil springs carried by said frames, a bottom wire extending across the front of said spring structure and secured to the coil springs, said coils being provided with a clip having a channel receiving said wire and a second channel curved on the radius of the coil, said clip being provided with tongues which are wrapped around said coil and said border wire respectively whereby the border wire is secured to said spring coil, a top wire secured to and extending across the top frame parallel to the front edge thereof, a plurality of band springs bowed out at the front edge of said spring structure having hinging connections at 115 120 125 130

over ends with said top and bottom wires respectively, said band springs being provided with slots in their ends, and a plurality of clips provided with a slot at one end and 5 a tongue at the other end, each of said clips being wrapped around one of said wires with the tongue thereof extending through a slot in one of said band springs and through the slot in the end of said clip and 10 affording a hinging connection for the ends of said band springs, all coacting substantially as described for the purpose specified.

2. A spring structure comprising top and bottom frames, coil springs carried by said frames, a bottom wire extending across the front of said spring structure and secured to the coil springs, a top wire secured to and extending across the top frame parallel to the front edge thereof, a plurality of band 15 springs bowed out at the front edge of said spring structure having hinging connections at their ends with said top and bottom wires respectively, said band springs being provided with slots in their ends, and a plurality of clips provided with a slot at one 20 end and a tongue at the other end, each of said clips being wrapped around one of said wires with the tongue thereof extending through a slot in one of said band springs and through the slot in the end of said clip 25 and affording a hinging connection for the ends of said band spring, all coacting substantially as described for the purpose specified.

3. A spring structure comprising top and bottom frames, a plurality of coil springs carried thereby, a bottom wire secured to and carried by certain of said coil springs, a top wire carried by the top frame and extending parallel to the front edge thereof, and a plurality of band springs having hinging connections at their ends with said top and bottom wires respectively, said band springs being bowed outwardly around the 40 top front edge of said spring structure, all coacting substantially as described for the purpose specified.

4. A spring structure comprising a plurality of coil springs suitably supported, a wire carried by certain of said coil springs, a wire carried by the tops of said springs, and a plurality of band springs having hinging connections at their ends with said top and bottom wires respectively, said band 45 springs being bowed outwardly around the top front edge of said spring structure, all coacting substantially as described for the purpose specified.

5. A spring structure comprising a plurality of coil springs suitably supported, a plurality of band springs having a hinging connection with the top of said spring structure at one end, and having at their other ends suitable connections with the spring

structure and being bowed outwardly 65 around the top front edge thereof, all coacting substantially as described for the purpose specified.

6. A spring structure comprising a plurality of coil springs, and a plurality of band springs connected at one end to the top of said spring structure and at the other end to said spring structure at a point below the top front edge thereof, said band springs being bowed outwardly around the 75 top front edge of said spring structure, all coacting substantially as described for the purpose specified.

7. In a spring structure, the combination with a plurality of coil springs suitably supported, a plurality of band springs secured at their ends to wires carried by said spring structure, and hinging connections for the ends of said band springs comprising clips provided with a tongue at one end 80 thereof and a corresponding slot at the other end thereof, the tongues of said clips passing through slots provided in said band springs and through the corresponding slots in the ends of said clips, each of said tongues being bent over upon the body of the clip, and each of said clips embracing one of said wires, all coacting substantially as described for the purpose specified.

8. A spring structure comprising top and bottom frames, coil springs carried by said frames, a bottom wire extending across the front of said spring structure and secured to the coil springs, auxiliary springs surrounding certain of said coil springs, said auxiliary springs being secured to the bottom frame at the lower end, the upper ends of said springs being secured to said bottom wire, a top wire secured to and extending across the top frame parallel to the front edge thereof, a plurality of band springs bowed out at the front edge of said spring structure having hinging connections at their ends with said top and bottom wires respectively, said band springs being provided with slots in their ends, and a plurality of clips provided with slots at one end and tongues at the other end, each of said clips being wrapped around one of said wires with the tongue thereof extending through a slot in one of said band springs and through the slot in the end of said clip and affording a hinging connection for the ends of said band spring, all coacting substantially as described for the purpose specified.

9. In a spring structure, the combination with a wire of a coiled spring and a clip comprising a body portion having a longitudinal channel adjacent one edge adapted 125 to receive said wire and a curved channel adjacent its opposite edge adapted to receive a coil of the spring, said clip having a cen-

tral tongue at its curved channel edge, the base of said central tongue corresponding in width to the chord of the said curved channel, and a pair of tongues at its longitudinal channel edge spaced to receive said central tongue between them when the tongues are folded.

In witness whereof, I have hereunto set my hand and seal in the presence of two witnesses.
